(57) **CLAIM**

The ornamental design for an extruder insert, as shown and described.

DESCRIPTION

FIG. 1 is a perspective view of an extruder insert showing my new design;

FIG. 2 is a front elevation view of an extruder insert showing my new design;

FIG. 3 is a top plan view of an extruder insert showing my new design;

FIG. 4 is an end view of an extruder insert showing my new design; and,

FIG. 5 is bottom plan view of an extruder insert showing my new design.

The broken line showing of a circle grouping is included for the purpose of illustrating non-claimed subject matter and forms no part of the claimed design.
